through to reach the flue and, by reason of the spacing with respect to the flue, the heated gases will be evenly distributed about the side walls of the heating drum, which comprise the portion thereof desired to be efficiently heated.

In order to prevent the heated gases passing directly upward from the burner to the top of the drum and out the flue, and to provide an insulating dead air space centrally of the drum and cause the gases to travel only through the apertures particularly positioned for that purpose in the baffle, there is provided an inner drum. Said inner drum has a bottom 22, a peripheral wall 23 and a top 24. It is adapted to be positioned within the heating drum and removable therefrom by mounting within the opening left in the top 12 of the drum and the opening in the baffle 20. Said inner drum is provided with central openings in both the bottom 20 and top, but the wall 23 thereof entirely closes off any passageway to the flue 19 other than through the apertures 21 in the baffle. The central opening is provided in the inner drum to permit removal therethrough of the flame spreader 25 by means of a cleaner rod 26 and cleaner pipe 27.

A top lid 28 is mounted upon the cleaner rod for closing the central opening in the top 24 of the inner drum. Thus, the heating drum is covered by its immovable top 12, the top 24 of the inner drum and the lid 28. By reason of the inner drum construction, ready access can be obtained to the burner for cleaning the same through removal of the lid 28. Removal of the inner drum allows access to be had to the entire inner surface of the heating drum for cleaning and inspection. At the same time, the inner drum provides a dead air space since the heated gases passing through the central opening therein are trapped within the walls 22, 23, 24 and 28, and, while some heat is lost due to conduction, no appreciable flow of heated gases occurs. Consequently, the entrapped gases in the inner drum will serve somewhat as an insulating medium to prevent excessive heat being generated from the top of the heating drum. However, I do not wish to be confined to the construction detailed above, as exactly the same results can be secured, without any removably mounted inner drum, by positioning a peripheral wall or drum between the baffle plate and the top, said wall or drum having a diameter substantially larger than said central openings in both top and baffle.

The burner body comprises a casting secured to and supported upon the bottom 11 of the heating drum. Said casting comprises an outer ring 30 which supports an inner annular oil cup 31 by spaced ribs 32. A burner ring 33 is seated within the annular oil cup 31 above which the flame spreader 25 is positioned. On one side of the oil cup there is cast therewith a pipe coupling 34 upon which there is connected an overflow cup 35 through a short pipe coupling 36. The overflow cup has an offset enlargement 65 which is connected with the overflow pipe 37, the short pipe coupling 36 being directly connected through the overflow cup, but not communicating therewith, with an inlet pipe 38.

Supported by the legs 13 below the bottom 11 of the burner drum, there is a combined heat deflector or shield and drip pan 39, said shield being spaced from the bottom 11 to provide an insulating dead air space therebetween and prevent the space below the burner under which the 70 chicks may huddle from being excessively heated

by the bottom 11 of the burner drum. Substantially centrally of the shield but slightly off center, there is a concave portion 40 which serves as a drip pan and through the center of which the short pipe coupling 36 projects, said concave portion being so positioned with respect to the burner as to catch any overflow of oil therefrom and cause it to enter the overflow cup 35 so as to escape through the overflow pipe 37. By reason of this construction, the inlet pipe 38 may be conveniently connected and disconnected from the overflow cup as well as from the overflow pipe, such connections and disconnections being made below the burner drum and shield 39. This arrangement is most desirable for convenience in 15 connecting and disconnecting the brooder from the oil pipe connections.

In order that the desired temperature may be maintained within the brooder canopy, the oil inlet pipe 38 is caused to extend upwardly 20 through an aperture 41 in that side of the canopy opposite the flue. Secured on the inner side of the upstanding portion of the inlet pipe there is provided a bracket 42 supporting thermostatic wafer 43, the bracket and wafer extending well 25 within the outer periphery of the canopy. Mounted upon the upper end of the pipe and exteriorly of the canopy there is a control valve mechanism comprising a sight feed 44, a shut-off valve 45 and a thermostatically operated valve 30 rod 46, the rod 46 being actuated by a thermostatic control lever 47 which is in turn actuated by the thermostatically actuated rod 48, said rod being adjustable with respect to the lever 47 by reason of the screw threads and thumb nut 49. 35 The valve lever is shielded by a cover 50 and its control is limited by maximum and minimum set screws 51. Through this means, the temperature of the air within the canopy may be automatically controlled through a thermostatically controlled oil valve conveniently positioned exteriorly of the canopy. Such adjustments and observations may be made at a convenient outside position for control of the heat interiorly of the canopy.

The invention claimed is:

1. An oil burning heating drum for brooders, including an oil burner mounted in the bottom of the drum, a flue opening adjacent the periphery thereof, a baffle plate mounted within said drum intermediate the top and bottom having an opening therethrough for permitting access to the burner from the top of the drum, said plate being provided with a plurality of apertures so located relative to the flue that the combined areas thereof are progressively increased with the increase in distance from said flue, and an inner drum positioned above the baffle plate within the heating drum having an annular peripheral wall extending from the baffle plate to the top of the drum for closing the space therebetween to prevent direct passage of gases from the burner through the opening in the baffle to the flue.

2. An oil burning heating drum for brooders, including an oil burner mounted in the bottom of the drum, a flue opening from the top adjacent the periphery thereof, a baffle plate mounted within said drum spaced from the top and bottom thereof and secured to the cylindrical wall, said baffle plate having a central opening and a plurality of passages surrounding said central opening through which hot gases may pass to said flue, an inner cylindrical drum co-extensive with the opening in said baffle plate and positioned thereabove provided with top and bottom plates 70

having central openings therein, said openings being concentric with the burner and of a diameter to permit removal of a portion of the burner therethrough, and a removable lid for closing the opening in the top plate of said drum, the bottom plate of said drum being adapted to close the opening in said baffle plate whereby the products

of combustion may pass directly upwardly through the passages in said baffle and about the wall of said drum to the flue, said drum providing a dead air space for insulating the top of the heating drum.
